[57] CLAIM

The ornamental design for an electronic indicator board
for gum-dispensing machines, as shown and described.

DESCRIPTION

FIG. 1 is a perspective view of an electronic indicator
board for gum-dispensing machines showing my new
design, as installed in a gum-dispensing machine that is
shown in broken lines for illustrative purposes only.
FIG. 2 is a perspective view taken from the top and left
side thereof;

FIG. 3 is a top plan view thereof;

FIG. 4 is a front elevational view thereof; and

FIG. 5 is a right side elevational view thereof.

The back of the board is plain and unornamented.

Fig. 3.

Fig. 2.

Fig. 5.

Fig. 4.
